UNITED STATES PATENT OFFICE

107,578

DESIGN FOR A FLASHLIGHT CASING

Howard M. Price, Toledo, Ohio, assignor to The Bridgeport Metal Goods Manufacturing Company, Bridgeport, Conn., a corporation of Connecticut

Application March 26, 1937, Serial No. 68,410

Term of patent 7 years

To all whom it may concern:

Be it known that I, Howard M. Price, a citizen of the United States, residing at Toledo, county of Lucas, State of Ohio, have invented a new, original, and ornamental Design for a Flashlight Casing, of which the following is a specification, reference being had to the accompanying drawing, forming part thereof.

Fig. 1 is a plan view of a flashlight casing, showing my new design;

Fig. 2 is a side elevation thereof; and

Fig. 3 is an end view looking from the left of Figs. 1 and 2.

The dominant features of the design are the general outline and configuration together with the surface ornamentation substantially as shown.

I claim:

The ornamental design for a flashlight casing, substantially as shown and described.

HOWARD M. PRICE.
